ARCHERY RACK

James J. Garner and Joseph Budd Garner,
Cheatowaga, N. Y.

Application January 8, 1957, Serial No. 44,446

Term of patent 3½ years

(Cl. D34—15)

Fig. 1 is a perspective view of an archery rack embodying our new design.

Fig. 2 is an elevational view of the front thereof.

Fig. 3 is a top plan view thereof.

Fig. 4 is a side elevational view thereof, viewed from the right of the archery rack as shown in Fig. 2, the left hand side being similar in appearance.

The dot-dash line showing of a bow and arrows is for illustrative purposes only.

We claim:

The ornamental design for an archery rack, substantially as shown and described.
